[57] CLAIM

The ornamental design for a combined sled and housing for a radio controlled winch, as shown.

DESCRIPTION

FIG. 1 is a top plan view of a combined sled and housing for a radio controlled winch showing my new design;

FIG. 2 is a front elevation view thereof;

FIG. 3 is a right side elevation view thereof;

FIG. 4 is a bottom plan view thereof;

FIG. 5 is a left side elevation view thereof; and

FIG. 6 is a rear elevation view thereof.
